Letter Patent No. 1774, dated June 16, 1863.

The schedule referred to in these Letters Patent and making part of the same.

To all whom it may concern.

Be it known, that I, Elomir J. May, of Lowell, in the County of Middlesex, and State of Massachusetts, have originated and designed a new pattern for carpets or other fabrics, of which the following is a full, clear and exact description, reference being had to the accompanying drawings, making part of this specification.

This pattern consists of two series of stylized figures each composed of figures, frames and regular work arranged in the particular form shown in the drawing.

The spaces between these figures are occupied by a regular ground work.

The colors employed for the different portions of the design may be varied to suit the taste and wish of the manufacturer.

What I claim as my invention, and desire to secure by letters patent, is the design or pattern for carpets or other fabrics herein set forth.
